UNITED STATES PATENT OFFICE.

SIMON DEUTSCH AND EDWARD L. GROSS, OF CHICAGO, ILLINOIS.

MECHANISM FOR OPERATING GATES, DOORS, OR OTHER CLOSURES.

1,311,113.

Specification of Letters Patent.

Patented July 22, 1919.

Application filed January 28, 1910. Serial No. 540,528.

To all whom it may concern:

Be it known that we, SIMON DEUTSCH and EDWARD L. Gross, both citizens of the United States, residing at Chicago, in the 5 county of Cook and State of Illinois, have jointly invented certain new and useful Improvements in Mechanism for Operating Gates, Doors, or other Closures, of which the following is a description.

10 Our invention relates to mechanism adapted to be operated at will for controlling elevators or other gates, doors or closures.

The object of our invention is to provide 15 a simple, cheap and reliable device of the kind described, and one not liable to become deranged or inoperative when in service.

To this end our invention consists in the 20 novel construction, arrangement and combination of parts herein shown and described, and more particularly pointed out in the claims.

In the accompanying drawings wherein 25 like or similar reference characters indicate like or corresponding parts:

Figure 1, is a side elevation of our device.

Fig. 2, is a plan view of the same.

Fig. 3, is a detail of a portion of the controlling mechanism.

30 Fig. 4, is a diagrammatic view of a convenient method of arranging the electric wiring of our device.

Fig. 5, is an enlarged detail of a simple locking mechanism for preventing reverse 35 movement of the operating mechanism of the motor.

Figs. 6, 7 and 8 are enlarged details of a convenient form of friction brake mechanism for our device.

40 Fig. 9 is a detail of an automatic cut-out switch for our device.

Fig. 10, is a perspective view of a slightly modified form of our device.

Fig. 11, is an enlarged end elevation of 45 the form of our mechanism shown in Fig. 10.

Figs. 12 and 13 are side and plan views respectively of the mechanism shown in Fig. 11.

50 Figs. 14, 15 and 16 are enlarged details of portions of the mechanism shown in Figs. 10 to 13 inclusive.

Figs. 17 and 18 are side and end views 55 respectively of a slightly modified form of our device.

Figs. 19 and 20 are side and end views respectively of another form of our device.

Fig. 21 is a diagrammatic view of a convenient method of wiring the form of our device shown in Figs. 19 and 20.

60

Fig. 22 is a perspective view of an elevator shaft and the associated mechanism showing my improvement with parts of the electric wiring etc. shown diagrammatically.

65

In the preferred form, our device consists of a movable power element or motor arranged to travel in a fixed path and adapted to coöperate independently with each of a series of fixed devices mounted adjacent said path and each controlling the 70 operation of a door or other closure. In the drawings our device is shown arranged for controlling the gates or guards of an elevator in which 1 is a portion of the elevator cage, 2 is a side wall of the elevator well 75 or shaft, 3 is a suitable base or frame rigidly secured to the cage 1. A motor or other power element 4 of any suitable form is mounted upon the frame 3 and connected by beveled gears 5—6 and spur gears 7—8 to a 80 pinion 10 preferably positioned near the side of the cage 1 with the shaft 9 on which it is mounted extending substantially parallel to the direction of movement of the cage. Any suitable means may be provided 85 adapted to coöperate with the pinion 10 for operating any one of the elevator gates or closures when the cage is in position at that particular closure.

In the form shown a shaft 11 is rotatably mounted in suitable 90 bearings 12—14 upon the wall 2 for each gate to be operated. The shaft 11 preferably extends substantially longitudinally of the elevator and is provided with a pinion 15 rigidly secured thereto, adapted to coöperate 95 with and be rotated by the pinion 10 when the elevator cage is in position to require the opening of that particular gate.

As shown the ends of all of the teeth upon the pinions 10 and 15 are beveled or 100 sharpened to facilitate engagement between the pinions and the pinion 15 is of sufficient length to insure suitable engagement and permit a reasonable variation in the position of the elevator cage. A drum 16 is 105 rigidly secured to the shaft 11 with a rope, chain or other suitable member 17 extending from the drum to the gate to be operated so that by rotating the shaft 11 the flexible member 17 will be wound upon the 110

drum and the gate opened. In the preferred construction shown, a second flexible member 18 is also provided and wound upon the drum 16 or equivalent means in the 5 opposite direction.

A suitable counter-weight is attached to the free end of the member 18 arranged to partially balance the gate where the gate moves upward in opening, or is otherwise 10 arranged to be closed by its own weight.

In the preferred construction suitable means are provided to prevent a too sudden and violent closure of the gate when released. As shown, a friction band 19 is provided upon the shaft 11 with a projecting part 20 adapted to engage a movable latch 21 secured to the bearing 12. The several parts are so constructed and arranged that when the shaft 11 is rotated to open the gate, 15 the latch 21 will merely move and permit the band 19 to turn freely with the shaft, when however, the shaft is rotated in the opposite direction the latch engages the part 20 and prevents further rotation of the band 25 19 in that direction, thereby checking the movement of the shaft and insuring the desired operation of the parts.

Suitable means are also provided to lock the operating parts of the motor against reverse movement so that when a gate is wholly or partially open the motor may be stopped without permitting the gate to return to its 30 normal position. Any suitable means may be provided for this purpose. In the form 35 shown, a finger 23 is pivotally attached to the frame 3 of sufficient length to engage the back of the beveled gear 6 so that when the gear 6 is rotated to open the gate the free end of the finger 23 will rest lightly upon 40 the back of the gear without interfering with its movement. In case however, the gear tends to move in the opposite direction the finger will jam against the back of the gear and lock it against movement in that 45 direction.

In the preferred construction an electric motor attached to the usual lighting circuit in the cage is provided for operating our device. The circuit for controlling the motor is diagrammatically shown in Fig. 4 in which 24 is a generator or other source of electric energy connected by the conductor 50 to a movable terminal 26. A conductor 27 connects the opposite pole of the generator 55 to the motor 4 thence by conductor 28 to the movable terminal 29. The terminals 26 and 29 are so arranged that a slight longitudinal movement will bring them into contact simultaneously with the contact 60 plates 30 and 31 which are connected by conductors 30' and 31' and an automatic cut-out 32 thereby closing the circuit to the motor and causing it to operate. As the closure nears the limit of its opening movement

a part upon the gate engages the part 33 65 of the cut-out 32 and opens the circuit thereby stopping the motor and limiting the opening movement of the gate. Any suitable means may be provided for moving the terminals 26 and 29. In the form shown, a 70 push button 35 which may be operated either by the hand or foot is provided in the cage with a part 36 having a beveled face adapted to engage the end of a part rigidly secured to the terminals to force them outward, a spring or other suitable means being provided to normally maintain the terminals at the inner limit of their movement. 75

In the form shown in Figs. 10 to 13 inclusive the motor 56 is connected by gears 37-38 to a pinion 39 arranged to coöperate with a rack 40 attached directly to the gate to be operated, the teeth of the pinion 39 and a portion of the rack teeth being beveled or sharpened at their ends, as shown in 85 Figs. 14 to 16. In this form the rack is of sufficient width to permit slight variations in the position of the cage. The wiring of the motor and the operation of this form of our device is substantially the same as hereinbefore set forth and requires no further 90 description.

In the form shown in Figs. 17 and 18 an electric magnet 41 is mounted upon an arm 42 rigidly secured to the drive shaft of the 95 motor 43 and a disk is rigidly secured to the winding drum 45 upon which the rope or chain 46 for operating the gate is wound, the several parts being constructed and arranged to operate as a magnetic clutch to transmit 100 power from the motor to the winding drum. The operation is substantially the same as hereinbefore described. In the form shown in Figs. 19 and 20, an arm 47 is pivotally attached at one end to the gate 48 with its 105 opposite end extending upward and positioned between a pair of suitable rollers 49 or otherwise maintained in position laterally but permitted to move longitudinally thereby providing for the free movement 110 of the gate which is mounted upon a slightly inclined track or otherwise provided with means for normally maintaining the same in a closed position. In this form the motor consists of a solenoid 50 the plunger 51 of 115 which is provided with a spring 53 or other suitable means arranged to normally hold the plunger 51 at the extreme outer limit of its movement. A lateral hook or finger 52 is provided near the free end of the plunger 120 51 suitably formed to normally avoid engagement with the rollers 49 or other fixed parts upon the wall of the elevator shaft but adapted to extend to, and engage the lever 47 when the solenoid is energized and there- 125 by open the gate and hold it open as long as the current is supplied to the windings of the solenoid. When the plunger 51 is re-

tracted the finger 52 is not adapted to initially engage the lever 47 and for this reason suitable means are preferably provided to prevent maintaining the electric circuit 5 through the solenoid windings when the movable mechanism is not in position to co-operate with the fixed mechanism. In the form shown, the contact plates upon the wall 2 are of only sufficient length to 10 operate with terminals upon the cage when the cage is in position at a door and to permit a reasonable variation in its position. At all other points it is obvious that the push button could not be operated to 15 close the circuit. The position of the cage therefore breaks the circuit and partially controls the operation of the mechanism permitting the plunger 51 to return to its normal position before the cage arrives at the 20 next gate which it may be desirable to operate.

It is obvious that our device may be applied to either freight or passenger elevators or under any conditions where doors 25 or gates are to be operated in connection with a movable car or cage, and where it is desirable to control the operating mechanism from the movable car.

Having thus described our improvement 30 it is obvious that various immaterial modifications may be made in our device without departing from the spirit of our invention, hence we do not wish to be understood as limiting ourselves to the exact form or 35 construction shown.

What we claim as new and desire to secure by Letters Patent is:

1. A device of the kind described comprising a movable motor, a closure, means for 40 locking the operating parts of said motor against movement in one direction, fixed mechanism adapted to periodically co-operate with said motor to operate said closure, and means for controlling the operation of 45 said motor.

2. A device of the kind described comprising a closure, a motor, means for locking the operating parts of said motor against movement in one direction, and means for 50 moving said motor in a fixed path, in combination with mechanism mounted adjacent said path adapted to periodically co-operate with said motor to operate said closure,

and means for controlling the operation of said motor. 55

3. A device of the kind described comprising a closure, a motor, means for locking the operating parts of said motor against movement in one direction and means for moving said motor in a fixed path, in combination with mechanism mounted adjacent 60 said path adapted to periodically co-operate with said motor to operate said closure, and means partially controlled by the position of said closure for controlling the operation of 65 said motor.

4. In an elevator, a motor carried thereby, gate-operating mechanism comprising a motor-operated driving element on the car and a revoluble gate-opening shaft on the 70 housing, means for causing said driving-element to co-operate with said shaft when the floor of the car is substantially level with the floor of the building, and means for closing the circuit through said motor. 75

5. In an elevator, a motor carried thereby, gate-operating mechanism comprising a motor-operated driving element on the car and a revoluble gate-opening shaft on the housing, means for causing said driving- 80 element to co-operate with said shaft when the floor of the car is substantially level with the floor of the building, and co-operating means on the car and housing for closing the circuit through said motor. 85

6. Gate-operating mechanism for elevators comprising a motor carried by the car, a shaft revolvably mounted on the housing of the elevator, means for operatively connecting said motor with said shaft to revolve the latter when the floor of the car is substantially level with the floor of the building, means for opening the gate when said shaft is revolved, means for closing the circuit through said motor when the floor 95 of the car is level with the floor of the building and means for opening the circuit when the gate is open.

In testimony whereof we have hereunto signed our names in the presence of two sub- 100scribing witnesses.

SIMON DEUTSCH.
EDWARD L. GROSS.
